UNITED STATES PATENT OFFICE.

ARTHUR W. BUSH, OF BOULDER, ASSIGNOR TO CALVIN W. LITTLE, OF DENVER, COLORADO.

WATCH-MAKER'S TOOL.

SPECIFICATION forming part of Letters Patent No. 281,967, dated July 24, 1883.

Application filed June 14, 1883. (No model.)

To all whom it may concern:

Be it known that I, ARTHUR W. BUSH, of Boulder, in the county of Boulder and State of Colorado, have invented a new and useful

5 Improvement in Watch-Makers' Tools, of which the following is a full, clear, and exact description, reference being had to the annexed drawings, forming a part of this specification.

10 This invention relates to a combination-tool for holding seconds-hands while reaming out the socket to fit the watch; also, for adjusting the ruby-pin or pin-jewel in the roller-table of a watch; and the invention consists of the 15 novel construction hereinafter described and claimed.

In the drawings, Figures 1 and 2 are plan views, and Fig. 3 an edge view, of my invention.

20 A indicates a flat piece of metal, bent or otherwise shaped to form a combined handle and curved spring, B, and having the separable arms C C, laid alongside each other and held in mutual contact by a sliding loop, D. A

small perforation, E, is formed through the 25 contact-surfaces of the arms, near their outer ends, as a recess for the seconds-hand G or ruby-pin to be grasped by the tool.

With this construction, when the loop is moved toward the handle, the outer ends of 30 the arms will be caused slightly to separate, so that the tool can be placed in engagement with the seconds-hand or ruby-pin, and when the loop is then moved outwardly the arms will be made to clamp the seconds-hand or 35 ruby-pin and hold it firmly. One of the arms is provided with a stop, F, to prevent the loop from being removed from the arms.

What I claim is—

The combination-tool consisting of the strip 40 A, having the spring-handle B, and arms C C, having a recess, E, between their contact-surfaces, and the loop D for confining the said arms, substantially as shown and described.

ARTHUR W. BUSH.
